[57] CLAIM

The ornamental design for a speaker grille and keypad for a portable radio or similar article, as shown and described.

DESCRIPTION

FIG. 1 is a front, top and left side perspective view of a speaker grille and keypad for a portable radio or similar article showing our new design;

FIG. 2 is a right side elevational view thereof;

FIG. 3 is a rear elevational view thereof;

FIG. 4 is a bottom plan view thereof;

The broken line showing of the portable radio is for illustrative purposes only and forms no part of the claimed design.

FIG. 1

*FIG. 3**FIG. 2**FIG. 4*
